UNITED STATES PATENT OFFICE.

HENRY B. KOPF, OF NEW HAVEN, CONNECTICUT.

PINEAPPLE-EYE SNIP.

1,115,838.

Specification of Letters Patent.

Patented Nov. 3, 1914.

Application filed August 3, 1914. Serial No. 854,683.

To all whom it may concern:

Be it known that I, HENRY B. KOPF, a citizen of the United States, residing at New Haven, in the county of New Haven and 5 State of Connecticut, have invented a new and useful Improvement in Pineapple-Eye Snips; and I do hereby declare the following, when taken in connection with the accompanying drawings and the characters of reference marked thereon, to be a full, clear, and exact description of the same, and which said drawings constitute part of this application, and represent, in—

Figure 1 a view in side elevation of a 15 pineapple-eye snip constructed in accordance with my invention, showing the jaws open. Fig. 2 an edge view of the instrument. Fig. 3 a view thereof in horizontal section through the jaws on the line *a—b* 20 of Fig. 2, and looking downward.

My invention relates to an improvement in pineapple-eye snips, the object being to provide a simple and effective instrument primarily designed for use in canneries, and 25 constructed with particular reference to avoid bruising the fruit around the eyes and to minimize the time, labor and fatigue of the operation in question.

With these ends in view, my invention 30 consists in a pineapple-eye snip having certain details of construction and combinations of parts as will be hereinafter described and pointed out in the claims.

My improved instrument which has the 35 general appearance of an ordinary pair of gripping pliers, is formed with two corresponding jaws 2, 3, located at the outer ends of bowed handles 4 and 5 secured together by a pivot 6 located at the bases of the 40 jaws, the handle 5 being provided with a curved extension 13 offering a rest and point of purchase for the outer edge of the hand of the user. The said jaws 2 terminate at their outer ends in sharp points 7 and have 45 the outer edges of their pointed ends beveled as at 8; while the inner edges of their ends are made straight and arranged so as to shut together. The inner margins of the respective jaws are adapted to form cutting 50 edges as the intention is that the device shall actually cut out the eyes rather than pull or tear them out. Each jaw is virtually skeletonized by the formation in it of a large clearance-opening 9 providing for

the ready escape of the extracted eye in 55 either direction. The opposing side walls of the respective jaws are arranged in line with each other at or about the transverse centers of the jaws as shown by comparing Figs. 2 and 3, whereby the jaws are prevented from being fouled and straight 60 lateral passages formed through the clearance-openings for the discharge of the extracted pineapple-eye in either direction, as described. By pointing the jaws as at 7 65 and beveling them as at 8, the jaws may be thrust into the fruit over the eyes thereof so as to make a clean cut without bruising the fruit about the eyes; while by furnishing each jaw with a relatively large clearance-opening the extracted eyes are left free 70 to work out in either direction without necessity of using the wrist to give the instrument a vigorous twist to discharge the extracted eyes from the snip, whereby the 75 time, labor and fatigue of using the instrument is greatly reduced, enabling a person to remove the eyes from a larger number of pineapples in a given time than has been possible with any of the devices at present 80 in use for the purpose.

As shown, the handles 4, 5, are provided toward their forward ends with outwardly projecting stud-like abutments 10 which incline slightly forward. These abutments permit the pointed jaws of the snip to be driven by a forward pressure of the hand, into the pineapple by a quick decisive movement, without closing the handles together by gripping them, which would have the effect 90 of prematurely closing the jaws. The handles, and hence the jaws, are normally held apart by means of a helical spring 11 interposed between the handles and having its end coils sleeved over retaining-pins 12, 12, 95 projecting inward from the inner edges of the handles, and, as shown, located in line with the inner ends of the abutments 10. It is not essential, however, that my improved instrument shall be provided with 100 the said abutments, nor that the spring 11 shall be arranged and retained in place as shown.

I claim:

1. A pineapple-eye snip provided with 105 co-acting pointed jaws each having a large clearance-opening and having their inner margins adapted to form cutting edges for

cutting out the pineapple-eyes which are then ejected transversely outward through the clearance-openings.

2. A pineapple-eye snip provided with 5 co-acting pointed and beveled jaws having their inner margins adapted to form cutting edges and each having a large clearance-opening, the opposing side walls of the respective jaws being arranged in line with 10 each other at or about the transverse cen-

ters of the jaws to assist the discharge of the pineapple-eyes outward through the clearance-openings of the jaws.

In testimony whereof, I have signed this specification in the presence of two subscr- 15
ing witnesses.

HENRY B. KOPF.
